(57) **CLAIM**

The ornamental design for an electric bicycle as shown and described.

DESCRIPTION

FIG. 1 is a front, right, and top perspective view of an electric bicycle showing my new design;

FIG. 2 is a rear, left, and bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged detailed view taken from the oval area 9 in FIG. 1;

FIG. 10 is an enlarged detailed view taken from the oval area 10 in FIG. 1;

FIG. 11 is an enlarged detailed view taken from the oval area 11 in FIG. 1;

FIG. 12 is an enlarged detailed view taken from the encircled area 12 in FIG. 2; and,

FIG. 13 is an enlarged detailed view taken from the encircled area 13 in FIG. 2.

The broken lines in the drawings depict portions of the electric bicycle that form no part of the claimed design.

The dot-dash lines in FIGS. 1-2 and 9-13 are provided for annotative purposes only to show the areas of enlargements. The dot-dash lines do not illustrate structures or subject matters and do not form part of the claimed design.

1 Claim, 13 Drawing Sheets
